TENT CONSTRUCTION

Cecil M. Wickstrum, Omaha, Nebr.

Application May 16, 1934, Serial No. 725,969

13 Claims. (Cl. 135—4)

This invention relates to tent frame construction, the primary object of the invention being to provide a tent frame of the foldable type, which will be strong and durable, novel means being provided for bracing the roof section of the tent, against excessive weight resulting from snow or ice collecting thereon.

Another object of the invention is the provision of a removable corner pole or post, capable of being readily positioned along the eaves bars of the tent frame, to support the tent, when it is impossible to position the usual corner spikes, over which the corner poles are placed, owing to the presence of head stones or shrubbery.

15 A further object of the invention is to provide means for removably connecting the ridge pole sections and eave bar sections to the truss columns, in such a way that the ridge pole and eave bars cannot become accidentally displaced.

20 Another important object of the invention is to provide a tent frame embodying a plurality of auxiliary or removable truss sections which may be employed when it is desired to support the roof or tent against excessive weight, caused by ice or snow collecting on the roof.

25 Still another important object of the invention is to provide a tent truss of a construction whereby all of the members of the truss are hinged, to the end that it is unnecessary to disconnect or disassemble the members, when the tent is being dismantled or erected.

30 A still further object of the invention is the provision of brace bars so arranged with respect to the truss sections and ridge pole sections, that collapse of the frame during the process of erection, and when connecting bars are being applied, will be prevented.

35 Still another object of the invention is to provide a tent frame capable of adjustment to various lengths, for various purposes.

40 With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

45 Referring to the drawings:

Figure 1 is a front elevational view of a tent frame constructed in accordance with the invention.

50 Figure 2 is a sectional view taken on line 2—2 of Figure 1.

Figure 3 is a plan view of the tent frame.

Figure 4 is a sectional view taken on line 4—4 of Figure 3.

Figure 5 is a sectional view taken on line 5—5 of Figure 1.

Figure 6 is a side elevational view illustrating an auxiliary supporting post as connected with an eaves bar.

Figure 7 is a sectional view taken on line 7—7 of Figure 6.

Referring to the drawings in detail, the tent frame forming the subject matter of the present invention, is designed primarily for use in the construction of a tent commonly known as a chapel tent, wherein the roof section thereof is usually curved.

In the construction of a chapel tent frame, truss sections such as indicated generally by the reference character 5 are provided, the number of truss sections being determined, by the length of the chapel tent desired.

Each of these truss sections embodies a truss column indicated by the reference character 6, to the upper end of which truss column, is connected a frame indicated at 7, the frame having openings in the side plates thereof.

The reference character 8 designates arch sections of the truss, each of which comprises curved rods 9 formed with inwardly extended ends 10, that fit in the openings formed in the frame 7, as shown by Figure 3 of the drawings.

The rods of which the arch sections are formed, are held in proper spaced relation with each other, by means of the metallic straps 11, that are shown as connected with the rods 9, near the end thereof.

At the outer ends of the arch sections 8, are corner posts 12, which posts are formed with caps, to which the rods 13 are welded, the rods 13 being formed with eyes 14, that extend beyond the sides of the corner posts.

These rods 13 also provide the securing means between the arch sections 8 and the corner posts, the rods of which the arch sections are formed, having their outer ends looped around the rods 13.

Slidably mounted on the truss column 6 of each truss, is a frame indicated at 15, which frame is formed with openings to accommodate the inwardly extended ends 16 of the brace sections 17, each brace section embodying a pair of rods, held in their proper spaced relation by the wide straps 18, which are secured near the ends thereof.

The outer ends of the brace sections are also formed with inwardly extended portions, fitted

in openings disposed in opposite sides of the corner posts, at points spaced from the upper ends of the posts, so that free pivotal movement of the posts with respect to the frame, will be 5 permitted at all times.

Brace rods indicated at 19, connect with the plates 20, that are in turn secured to the curved rods 9, the free ends of the brace rods 19 being formed into laterally extended end portions that 10 pass through openings in the frame 15, thereby bowing the arch sections, and holding the arch sections in their bowed positions, properly shaping the frame.

In order that the brace rods will be held against 15 accidental displacement, sliding loops 21 are provided, which sliding loops move to positions adjacent to the free ends of the brace rods, preventing the rods from moving laterally, after they have been positioned.

20 Secured to the frame 7, is a substantially short rod 22, which has its ends formed into eyes 23, which eyes are designed to accommodate the hooks 24 of the ridge pole sections 25. These ridge pole sections are tubular, one of the sections carrying a pin 26, over which the adjacent ridge pole section is positioned, in connecting the ridge pole sections.

These hooks 24 are so constructed that when 30 they are positioned, the inner ends of the hooks must be lowered, allowing the ridge pole sections to swing inwardly before they may be removed from the eyes 23.

The eave bars are of a construction identical with the construction of the ridge pole sections, 35 and therefore further detailed description of these sections, is believed unnecessary.

Connecting rods 27 are pivotally connected with the ridge pole sections and associated columns 6 and with the eave sections and associated corner posts, the free ends of said connecting 40 rods being extended inwardly, where they pass into openings thereof formed in the respective associated members.

These connecting rods are so constructed that 45 they prevent collapsing of the frame, during the erection of the tent, or during the operation to disassemble the tent.

The tent frame also includes auxiliary arch or 50 truss sections, each of which comprises a pair of pivotally connected members 29, connected by means of the hinge sections 30. Each of these hinge sections is formed with a downwardly extended lug, the inner surface of the cooperating lugs, being curved to fit around a ridge pole section 55 associated therewith.

At the outer ends of the auxiliary arch sections, are clamping members 32, each of which being substantially U-shaped to fit over the eave bars of the tent frame structure, as shown by Figure 4 of the drawings.

60 Set screws 33 extend through the clamping members, and engage the eave bars with which the auxiliary truss is used, thereby securing the auxiliary truss or arch in position.

65 From the foregoing it will be seen that due to this construction an auxiliary arch or truss may be readily and easily secured within the frame of the tent, to support the roof or tent against excessive weight caused by ice or snow collecting on the roof.

70 In connection with the corner post, spikes, such as indicated at 34 are used, the spikes being driven into the ground surface in such positions that the corner posts may be fitted thereover, and secured by means of set screws 35.

In the erection of a tent frame, should it be found that it is impossible to position the spikes, owing to the presence of a head stone or shrubbery, an auxiliary post such as indicated by fingers 6 and 7 of the drawings, is used. This auxiliary post includes a main section 36, which is formed with a curved clamp 37 at its upper end, the clamp being so constructed that it will fit around an eave bar, where it is secured in position by means of set screw 38.

10 Having thus described the invention what is claimed is:

1. A tent frame construction comprising truss sections, each truss section including a column, roof sections pivotally connected to the upper 15 end of the column, a frame slidably mounted on the column, brace rods connected with the frame, means for connecting the outer ends of the brace rods and the outer ends of the roof sections, brace rods extending from the roof sections to the 20 frame, and posts at the ends of the roof sections.

2. A tent frame construction comprising truss sections, each of said truss sections comprising roof sections, a column to which the roof sections are pivotally connected, a frame slidably through- 25 out the length of the column, brace rods, means for pivotally connecting the brace rods and roof sections, means for pivotally connecting the brace rods to the slidable frame, and means for holding the frame in its active position.

3. The combination with a tent frame having a ridge pole and eaves bars, an auxiliary arch member including hingedly connected sections, a clamping member disposed intermediate the ends of the arch member and adapted to clamp 35 the ridge pole, and clamps at the ends of the arch member and adapted to clamp the eaves bars of the tent frame.

4. The combination with a tent frame having a ridge pole and eaves bars, an auxiliary arch in- 40 cluding arch sections, a hinge connecting the adjacent ends of the arch sections, curved ridge pole engaging members forming a part of the hinge and adapted to clamp the ridge pole when the outer ends of the arch are moved down- 45 wardly, and means at the outer ends of the arch for securing the ends of the arch to the eaves bars.

5. The combination with a tent frame having a ridge pole and eaves bars, of an auxiliary arch 50 comprising pivotally connected sections, means for securing the arch to the ridge pole, U-shaped clamps at the ends of the arch sections and adapted to fit over the eaves bars, and means for securing the U-shaped clamps to the eaves bars. 55

6. A tent frame construction comprising truss sections, each truss section including a truss column, truss bars, means for pivotally connecting the truss bars to the upper end of the truss column, corner poles, means for connecting the 60 truss bars to the corner poles, bracing members pivotally connected with the corner poles, and means for slidably and pivotally connecting the bracing members to the truss column.

7. A tent frame construction comprising truss 65 sections, each truss section including a central truss column, truss arch bars pivotally connected with the truss column, corner posts to which the truss arch bars are connected, horizontally dis- 70 posed eye members at the tops of the corner posts and truss columns, ridge pole, and eaves bars, hooks at the ends of the ridge pole and eaves bars, said hooks adapted to hook into the horizontal eye members, removably connecting the ridge pole and eaves bars to the truss sections.

8. The combination with a tent frame having a ridge pole and eaves bars, of an auxiliary arch embodying sections, a hinge connecting the sections, clamping means carried by the hinge and adapted to clamp the ridge pole of the tent when the free ends of the arch are moved downwardly, and clamps at the outer ends of the auxiliary arch, securing the arch to the eaves bars.
9. The combination with a tent frame having a ridge pole, and eaves bars, of an auxiliary arch embodying curved sections, means for pivotally connecting the inner ends of the curved sections, lugs at the inner ends of the curved sections, said lugs adapted to move towards each other to clamp the ridge pole when the outer ends of the arch are moved into engagement with the eaves bars, and clamps on the auxiliary arch for clamping the eaves bars.
10. The combination with a tent frame having eaves bars, of an auxiliary supporting member, a clamp at one end of the auxiliary supporting member and adapted to clamp over an eaves bar,
- 5 removably clamping the supporting member to the frame.
11. A tent frame construction comprising truss sections, said truss sections having eyes, corner posts, ridge poles and eaves bars, hooks at the ends of the ridge poles and eaves bars, and adapted to hook into the eyes, connecting the truss sections and corner posts of the frame.
12. The combination with a tent frame having a ridge pole and eaves bars, an auxiliary sectional arch member, a clamping member attached to adjacent ends of the sections and adapted to clamp the ridge pole, and clamps at the ends of the arch member, adapted to clamp the eaves bars of the tent frame.
13. The combination with a tent frame having a ridge pole and eaves bars, an auxiliary arch member embodying sections, a hinge member connecting the sections of the arch member and having curved ridge pole clamping members, and means for securing the free ends of the arch members to the eaves bars.
